Mo., assignors to John E. Mitchell Company,
Dallas, Tex., a corporation of Missouri

Application February 9, 1942, Serial No. 430,000

23 Claims. (Cl. 12—50)

The general object of this invention is to provide novel heel building mechanism for use in a heel building machine of the character described in our prior application, Ser. No. 421,108, filed December 1, 1941, when such machine, which, as we have explained in said application may be made readily adaptable for building various types of heels, is organized for building decked heels of any desired height for ladies' shoes. The present application is a continuation in part of the application referred to, in that it is directed to certain mechanism illustrated and described in said prior application but not claimed therein.

The machine of our prior application is characterized by an endless series of clamp carriers mounted to travel in stages around the machine, forty-two of such carriers being employed, the rest period of the carriers, after each stage of movement thereof, being employed by the operator in assembling pasted lifts into a heel-blank and then depressing a foot treadle to close a clutch on a drive shaft, whereupon various automatic mechanisms are brought sequentially into operation to move the freshly-built heel-blank onto a carrier, to clamp the heel-blank, to unclamp and eject from the machine a heel-blank which has made the circuit of the machine, and to cause a stage movement of the carriers to bring an empty carrier into position to receive a freshly built heel-blank and a succeeding heel-blank to that previously discharged into position to be unclamped and ejected from the machine.

The present invention is directed to that part of our machine constituting the heel-forming mechanism, and to the mechanism cooperating therewith for correctly positioning the lifts of a freshly-built heel-blank and holding them in their correct assembled position while being clamped and during the initial stages of movement of the heel-blank around the machine, sufficient as to time to permit the paste between the lifts to dry to an extent that will prevent displacement of the lifts under the pressure of the clamping means during the remainder of the travel of the heel-blank around the machine.

As to the heel-forming mechanism proper, the invention consists in providing means which will enable lifts for any size, shape, or height of heels for ladies' shoes to be readily and accurately assembled into a heel-blank, beginning with the top, or tread, lift and proceeding up to the base, or largest, lift. To this end, we employ a series of heel-forming plates designed to be assembled

in superimposed relation in two ranks, or piles, lying opposite each other, and adjustably secured in holders, each plate being substantially of the thickness of an average lift employed in building such heels, and so shaped that when assembled as described they will provide a breast-plate against which the breasts of the lifts are placed in the assembling operation, and a recess having upwardly-diverging side walls stepped in accordance with the decking of the heel-blank; corresponding steps on opposite sides of the recess being designed to receive and engage opposite sides of a heel lift at the breast portion, insuring that each succeeding lift shall project the proper distance beyond the sides of the lift immediately below it; and as the engagement of the breasts of the lifts with the breast plate of the heel-former assures the accurate overlapping of successive lifts at their rounded, or rear, sides, a decked heel of any size, shape, or height, can be readily built up without any manual adjustments of the lifts on each other being required of the operator. However, slight inaccuracies in the positions of the lifts may occur in the assembling operation, and these are overcome, or corrected, by moving the heel-blank into engagement with heel-engaging means conforming to the contour, incline and height of the heel-blank at its rear side, whereby the breasts of the lifts are forced against the breast-plate, and accurate positioning of the lifts secured, as later described.

The heel-forming mechanism described is mounted on a reciprocating plate, and in the operation of the machine is automatically moved inward to carry the assembled lifts beneath a clamping plate mounted on a clamp carrier, which clamping plate is then automatically depressed to clamp the freshly-built heel-blank.

As to the means for holding the lifts in position while the heel-blank is being clamped, and for a certain length of time thereafter, the invention consists in providing a series of back-bars superimposed upon each other in stepped formation, i. e., so as to form an ascending series of steps receding inwardly, or in a direction away from the operator, to conform to the upward and outward incline of the rounded side, or back, of the heel-blank, and each of the back-bars, forming one of said steps, being of the thickness of an ordinary lift used in building the heel-blanks, and therefore of the same thickness as the heel-forming plates constituting part of the heel-former. These back-bars when assembled and secured in a holder are adjustable as a whole,

toward and from the heel-former, so that they may be accurately positioned to be engaged by the back of the heel-blank when the latter is moved by the heel-former into position to be clamped. These back-bars, when assembled and adjusted in position, may be collectively considered as a holder and guide for the freshly-built heel-blank. That is to say, they act to prevent displacement of the lifts when clamping pressure is applied to the heel-blank, and to maintain the lifts in their correct assembled position for a portion of the distance the heel-blank travels around the machine. The period of time during which the heel-blank remains in contact with the back-bars is sufficient to permit the paste between the lifts to partially set, so that thereafter they will be held by the paste itself with sufficient firmness to prevent displacement of the lifts for the remainder of its travel around the machine. To enable these back-bars to act as a guide during the initial portion of the movement of the heel-blank around the machine, one end of the assembled back-bars is located directly opposite the heel-former, and after the heel-blank is clamped, the length of these back-bars is such that, in the machine shown, four stage movements of the endless series of carriers will occur before the heel-blank passes beyond, and out of contact with, the back-bars. In other words, their length is sufficient to accommodate four heel-blanks at one time. This length may be increased or diminished as may be found desirable. However, a less length of the back-bars than that shown would probably not give the paste time to set sufficiently to prevent in all cases displacement of one or more lifts after a heel-blank has passed out of contact with the back-bars.

In the drawings—

Fig. 1 is a plan view of a machine embodying our invention, the bin for containing the lifts to be pasted, assembled and clamped being omitted for clearness of illustration;

Fig. 20 is a section on line 20—20 of Fig. 19.

Referring now to the drawings, the numerals 3, 4, Figs. 1, 2 and 3, indicate, respectively, side frame members of the machine, in suitable bearings in which is mounted a main drive shaft 5, on one end of which is secured a pulley 6 which is driven by a belt 7 from a source of power (not shown). Beside pulley 6 is mounted on the shaft a loose pulley 8, a belt shifter 9 being employed to shift the belt from one pulley to the other, according to whether the machine is to be driven, or its motion stopped. Mounted on the drive shaft 5 near its opposite end is a clutch 10, comprising a loose clutch member 11 and a fast clutch member 12. The numeral 13 indicates a foot treadle to be actuated at will by an operator, which is secured at its inner end on a rock-shaft 14 pivotally supported in hangers 15 depending from a cross-bar 16 secured at its ends to the frame members 3, 4 of the machine. Also secured on rock-shaft 14 adjacent the head of the treadle is a rocker-arm 17 extending downward from the rock-shaft, and pivotally connected at its lower end to one end of a connecting bar 18, the other end of which is secured to a depending rocker-arm 19, the upper end of which is secured to a rock-shaft 20 supported in bearings in the frame members 3, 4. The lower end of rocker-arm 19 is pivotally connected to one end of a connecting bar 22, the other end of which is pivotally connected to the lower end of a rocker-arm 23, which depends from and is integral with a circular cam member 24 (Figs. 3 and 5), the outer face of which is provided with cam surfaces working against complementary cam surfaces on a fixed cam member 26 mounted on the frame of the machine. The cam member 24 is loosely mounted on the drive shaft 5 and abuts against the hub 27 of a sprocket gear 28, said hub and gear being loose on shaft 5. When the treadle 13 is depressed, the connecting bar 18 is moved to the rear, moving the rocker-arm 19, connecting bar 22 and rocker-arm 23 in the same direction. This movement causes the cam member 24 to be rotated and its cam surfaces to ride over the complementary cam surfaces on the fixed cam member 26, thereby moving its hub 27 into engagement with the side of the sprocket gear 28 and moving the latter inward, or toward the right in Fig. 3, causing the loose clutch member 11 to be moved into frictional engagement with the fast clutch member 12, which is constantly rotated by the drive shaft 5. The loose clutch member 11 and the sprocket gear 28 have a common hub 29, so that when the loose clutch member is rotated by engagement with the fast clutch member 12 the sprocket gear 28 will be caused to be rotated. Secured on a cross-shaft 30 (Fig. 5), supported in bearings on the frame members 3, 4, is a sprocket gear 31, considerably larger in diameter than the sprocket gear 28, and which is operatively connected to the latter by means of a sprocket chain 32. Secured on

75 the inner side of the sprocket 31 is a small

sprocket wheel 33 (Fig. 6). Located above the cross-shaft 30 and rotatably mounted in bearings in the frame members 3, 4, is a cam shaft 34 on which is loosely mounted a relatively large sprocket wheel 35 which is operatively connected to the sprocket wheel 33 by a sprocket chain 36. Mounted on this cam shaft 34 are a number of cams, which are brought into operation in a given order, so that when the cam shaft is rotated the various operations of the machine will be caused to occur in a given sequence. As the operation of all of these cams is fully described in our prior application, only those cams, to be later referred to, which operate the mechanisms involved in the invention to which the present application is directed will be described in this specification.

The numeral 37 (Fig. 5) indicates a coil spring, one end of which is secured to the rock-shaft 14 and the other to the rocker-arm 19. In the operation of the machine, the treadle 13 is held in a depressed position only momentarily and when released, the spring 37, which had been placed under tension when the treadle was depressed, operates to return the treadle and the cam faces on cam member 24 to normal position, thereby permitting the loose clutch member 11 to separate from the fast clutch member 12. The return movement of the treadle 13 is arrested by an adjustable stop screw 39 which is adapted to be engaged by the lower end of rocker arm 19. The fixed clutch member 26 may be secured in adjusted positions by means of a simple clamp 38 (Fig. 3).

Referring more particularly to Figs. 4, and 11 to 13, the heel lifts 40 are first pasted and then assembled on a base plate 41 with their breast sides inserted between two sets of heel-forming plates 42, 42, mounted one upon the other in holders 43 and clamped therein by means of set screws 44. In building up a heel-blank according to the present invention, the lifts are assembled in order from the bottom, or tread portion, to the upper portion, or base, of the heel. To enable the heel-blanks to be built up in the manner described, each of the heel-forming plates 42 (Fig. 19) is provided at its inner end with a portion 42^a which serves as a breast plate, and with inward-extending projections 45 which, in the assembled condition, diverge from each other in an upward direction to form a recess 42^b corresponding to the shape of the heel at the sides of the breast. The portion 42^a of the lowermost heel-forming plate is thicker than the plate 42 proper, as shown by Fig. 18, to allow said portion to extend below the bottom of the holder 43 in which it is mounted and lie flush against the surface of the base plate 41. The inner side of the projection 45 of all of the heel-forming plates is slightly inclined in an upward direction, as indicated at 42^c. Each of the plates 42 is approximately the thickness of an average heel-lift, the two series of projections 45 thus forming stepped recesses for receiving the lifts in order from the smallest to the largest lift employed in building the heel-blank. As will be understood, the inclined surfaces of the projections 45 cause the side walls of the recess 42^b to have a general incline conforming to the incline of the sides of the decked heel-blank. The holders 43 are mounted on the inner end of a movable support 46 which is mounted to slide in guides 46^a over the top of the base plate 41. The support 46 carrying the holders 43 with the heel-forming plates 42 clamped therein will hereinafter be referred to as a heel-former. After a heel-blank

has been assembled on the base plate 41, the first operation that occurs upon depressing treadle 13 is the movement of the heel-former inward to carry the assembled heel-blank into position on a travelling heel-clamp carrier 47, shown in all of the main views of the drawings, and the mechanism for effecting this operation will now be described.

Secured on cam shaft 34 (Fig. 8) is a cam 10 48 having a cam groove 49 formed in the face thereof. Pivoted at its lower end on the shaft 30 is an actuating lever 50, the upper end of which is pivotally connected at 51 to the inner end of a connecting rod 52, the other end of 15 which is pivotally connected at 53 (Fig. 11) to the lower end of a crank-arm 54, the upper end of which is secured on a rock-shaft 55 mounted in bearings 55^a provided on vertical frame members 55^b at the front of the machine. A second crank-arm 54^b is similarly secured on rock-shaft 55 and its upper end is pivotally connected to one end of a link 56, the other end of which 20 link is pivotally connected to a lug 57 carried by and projecting downward from the bottom of the support 40. As the cam shaft 34 is rotated through the medium of sprocket 35 and sprocket chain 36 from the sprocket 33, as previously described, the cam 48 will be turned. Mounted on the actuating lever 50 is a roller 58 which 25 engages in the cam groove 49, and as the high part of this cam groove passes over the roller 58 the actuating lever 50 will be moved toward the front of the machine, thereby partially rotating the rock-shaft 55 and through the medium of crank-arm 54^b and link 56 moving a heel-former inward and the heel-blank from the base plate 41 onto the bottom of the clamp carrier 47. In the continued revolution of cam 48, 30 the low part of cam groove 49 will engage roller 58 and return the heel-former to the normal position shown in Fig. 11. Just prior to the return movement of the heel-former the machine 35 operates to clamp the heel-blank deposited on the clamp carrier 47, and the means for effecting 40 this clamping operation will now be described, referring particularly to Figs. 7 and 11.

Pivotedly mounted on a cross-shaft 59 located at the rear part of the machine is a lever arm 60 which extends well toward the front of the machine and at its inner end is bifurcated (Fig. 1), the two arms 61 of this bifurcated end being connected, respectively, at 62 to the upper ends of two links 63 located on opposite sides of a plunger 64, and being connected at their lower ends to a cross-pin 65 passing through said plunger. The plunger 64 is slidably mounted in bearings 66 on the frame of the machine. Secured on the cam shaft 34 is a cam 67 the peripheral face of which normally engages a wear 50 plate 68 secured on the under side of the lever arm 60. As the cam 67 rotates, its high point passing under and in engagement with wear plate 68 raises the inner end of lever arm 60 which in turn, through links 63, raises the plunger 64, which operates to actuate the clamping mechanism by the following means:

A rack-bar 69 (Fig. 11) slidably mounted in guides 70 engages a spur gear 71 mounted in bearings 72. A companion rack-bar 73 slidably mounted in guides 74 engages the spur gear 71 on the opposite side to that engaged by rack-bar 69. An interiorly screw-threaded boss 75 on rack-bar 69 receives the lower screw-threaded portion of a rod 76, which is located above and 75 in line with the plunger 64, so that when the

latter is raised, as described, its upper end will engage the lower end of rod 76 and raise it, thereby raising rack-bar 69 and lowering rack-bar 73. The latter, as will presently appear, is provided with means for engaging and moving the clamping mechanism into clamping position on a heel-blank.

Each of the heel clamp carriers previously referred to is provided on its under side with rollers 71, which run on tracks 78 supported on the frame of the machine, and which extend entirely around the machine, as shown by Fig. 1. These clamp carriers are pivotally connected together in a manner to form an endless conveyor. Slidably mounted in the sides of each clamp carrier are two parallel bars 81 which are connected at their upper ends by a cross-bar 82 and at their lower ends by a cross-bar 83, thus providing a slidable clamping frame. Secured at their upper ends in, and projecting well below the under side of each carrier 47, are two parallel rods 84, which are connected at their lower ends by a cross-bar 85. Formed integral with the cross-bar 83 at each end thereof, respectively, are two sleeves 86 which are slidably mounted on the rods 84. Loosely mounted in the cross-bar 82 of each carrier is a pin 87, the head 88 of which is adapted to be engaged by the upper side of cross-bar 82 when the clamping frame is raised. Pivotally mounted on the lower end of pin 87 is a clamp plate 90, between which and the under side of cross-bar 82 is interposed a coil spring 91. The clamp plate 90 is of the type described and claimed in the patent to Dennis Parks, No. 2,176,560, dated October 17, 1939, and when forced downward into engagement with the base of the heel-blank, indicated in the views where shown by the letter H, its construction is such as to enable it to engage the hollowed-out portion of the base at the breast of the heel to afford a firm engagement of the clamp plate with the entire surface of said base. At the same time, the clamp plate will make a flush engagement with a perfectly flat base, as in clamping heel-blanks for men's shoes.

Secured at its upper end on the under side of each clamp carrier 47 is a rack-bar 97, which at its lower end is secured in the cross-bar 85. Projecting downward from the cross-bar 83 are two short parallel arms 98 between which is rotatably mounted a pinion 99 on a cross-pin 100. Pivotally mounted between arms 98 at their lower ends is a ratchet 101 which normally engages the teeth of pinion 99 and is yieldingly held in such engagement by a spring 102 (Fig. 10) engaging a tail piece 104 on said ratchet. Assuming the operator has built up a heel-blank on base plate 41, he depresses foot treadle 13, and through the operations of the mechanisms previously described places cam shaft 34 in operation. Cam 48 on said shaft now operates to cause the heel-former to be moved inward from the position shown in Fig. 11 and deposit the heel-blank on one of the clamp carriers 47 which, in the operation of the machine has been brought to rest immediately in front of the heel-former. Cam 67 (Fig. 7) now operates to raise the outer end of lever arm 60, which by means of links 63 raises plunger 64 into engagement with the lower end of rod 76 and raises it and with it the rack-bar 69, causing rack-bar 73 to be moved downward. Projecting outward from the upper end of this rack-bar is an arm 105 which extends over the cross-bar 83 and normally at some distance above the same, as shown by Fig. 11, and in the down-

ward movement of rack-bar 73 engages said cross-bar and draws the bars 81 and cross-bar 82 downward to carry the clamp plate 90 into engagement with the upper side of the heel-blank

5 and then to place spring 91 under tension to cause it to exert the proper pressure on the clamp plate. Ratchet 101, which rode over the teeth of pinion 99 as the latter was rotated by engagement with the teeth of rack-bar 97 in the downward movement of the clamping frame, now engages behind a tooth of the pinion and prevents the latter from being rotated in the opposite direction and thus securely locks the clamp in its clamped position.

10 The screw-threaded rod 76 is vertically adjustable in the boss 75 by means of a thumb-screw 239 (Figs. 2 and 3) on its upper end, to regulate the throw of the clamp plate 90 in accordance with the height of the heel-blanks being built. A gauge 231 provided with numbered graduations, in conjunction with an indicator 232 on the rod enables the operator to properly adjust rod 76 relative to the plunger 64. Fig. 11 shows the open, or raised, position of clamp plate 90 on an empty clamp carrier, and its clamped position on a heel-blank immediately beyond. The latter position of the clamp plate is also shown in Fig. 14. Immediately after the descent of the clamp plate on the heel-blank, the low part of cam 48 will pass over roller 58 and cause the heel-former to be returned to the position shown in Fig. 11. As each heel-blank is clamped, it is moved forward in the operation of the machine a distance sufficient to bring an empty clamp carrier opposite the base plate 41, while at substantially the same time a clamped heel-blank, which has travelled around the entire machine in order to give the paste between the lifts time to set, and arrived at a discharge point, or chute, 106 (Fig. 1) will 15 be released and ejected from its clamp carrier moved into position, the clamp carrier from which the heel has been discharged becoming the empty carrier next to receive a heel-blank. All the operations 20 of the machine occur in stages, and while the clutch members 11 and 12 are momentarily held in engagement by depression of treadle 13. However, the time interval between the various operations is very slight, depending upon the setting 25 of the cams on the cam shaft, and in some instances, as in the clamping of a fresh heel-blank and the discharge of a dried, or completed heel, the two actions occur almost simultaneously. The mechanism for effecting the travel in stages 30 of the endless series of clamp carriers will now be briefly described, as this mechanism, of itself, forms no part of the present invention, being fully described and claimed in our application referred to.

35 Referring to Fig. 1, the machine is provided at opposite ends with two upright stub shafts, 107, 108, respectively, and rotatably mounted thereon are two large sprocket wheels 109 and 109^a, respectively, which are provided in their peripheries 40 with equi-distant recesses 110 which engage lugs on the corners of the clamp carriers 47, these pivotally-connected carriers thus forming an endless-chain carrier, or conveyor. Fixedly secured to the hub of each sprocket wheel is a 45 ratchet wheel 111, from each of which projects a crank-arm 112, the outer ends of these crank-arms being connected to opposite ends of a connecting rod 113, which is provided with a cam surface 114. Mounted on each of the crank- 50 arms 112 is a spring-pressed ratchet 115. Pro-

55

60

65

70

75

jecting inward from connecting rod 113 is an arm 118 to which are secured the ends of two coil springs 119, the opposite ends of which are secured to a fixed arm 120 on a frame member

121. Pivotedly mounted on member 121 is a stop-arm 122 provided on its outer end with a roller 123 which is normally pressed toward the periphery of wheel 109 by a spring 124. Normally, roller 123 rests in one or the other of the recesses 110 of wheel 109, in which position it stops the rotation of the wheel, and hence the movement of the endless series of clamp carriers. On the under side of stop arm 122 is a roller 126 which is adapted to be engaged by the cam surface 114 to raise stop-arm 122 and release roller 123 from engagement with a recess 110 to permit wheel 109 to be rotated. The rotation of wheel 109 is effected as follows:

Secured on the cam shaft 34 is a cam 150 (Figs. 1 and 8) and below this cam is a lever arm 151 which is pivotally mounted at its inner end on a front frame member of the machine. Mounted on the upper side of this lever arm is a wear plate 152 which, when the cam shaft 34 is rotated, will be engaged by the high portion of cam 150 and cause the outer end of arm 151 to be depressed. Pivotally connected at its lower end at 153 to the outer end of lever arm 151 is a pull rod 154, which at its upper end is pivotally connected at 155 with one arm 156 of a bell-crank lever 157, pivotally connected at its elbow at 158 on the lower end of a frame support 159. The other arm 160 is pivotally connected at its upper end to one end of a link 161 the other end of which is pivotally connected to a boss 162 secured on the connecting rod 113 (Fig. 9). As the cam shaft 34 rotates, the high point of cam 150 will engage wear plate 152 and force the outer end of lever arm 151 downward, causing pull rod 154 to turn bell-crank lever 157, and move connecting rod 113 to the left (Fig. 1). In this movement of the connecting rod ratchets 115 will be moved by crank-arms 112 over the teeth of ratchet wheels 111 and finally engage behind one of said teeth. This movement of the connecting rod places coil springs 119 under tension by extending them, and at the same time causes cam surface 114 thereon to ride under roller 126 and raise stop-arm 122, disengaging its roller from a recess 110 in sprocket wheel 109. When the low point of cam 150 reaches wear plate 152, the power stored in springs 119 by the previous movement will be exerted to move connecting rod 113 to the right thereby, through the ratchet mechanism described, turning the wheels 109 and 109^a clockwise and causing the movement in the same direction of the endless series of clamp carriers. The movement to the right of connecting rod 113 also acts to release stop-arm 122, which is forced downward by its spring to enable its roller 123 to engage in a recess 110 in sprocket wheel 109 succeeding that in which it had previously rested, and thus stop the rotation of the sprocket wheels and movement of the endless carrier. The cam shaft 34 is, of course, rotated through a single cycle with each depression of treadle 13, and this rotation is initiated and stopped through the medium of automatic clutch and stop mechanism, indicated generally by the numeral 139 in Figs. 1 and 6, which is governed by a clutch-control bar 132, actuated from rock-shaft 20. This clutch mechanism is fully described in our prior application referred to, and as it forms no part of the present invention, it is not deemed necessary to more particularly illustrate and describe the same, as automatic clutches

for producing single revolutions of a driven shaft are well known, and any such conventional clutch, placed in operation on depressing treadle 13, could be employed.

In the operation of the machine in building heel-blanks, the movement and stoppage of the endless carrier above described will have brought a clamped and dried heel-blank to rest opposite the opening to the chute 156 (Figs. 1, 2 and 4) where it is to be unclamped and discharged. The unclamping and ejecting mechanisms are not illustrated or described in the present case, as they are not involved in the invention claimed herein, are fully illustrated, described and claimed in the parent application, and their operations are not necessary to the performance of the present invention. We will now describe the method of building heel-blanks and maintaining the pasted lifts in their proper assembled position while being clamped and during a portion of the movement of the endless carrier.

Referring to Fig. 1, there is mounted on a support, or table, 205 at the front of the machine a paste applying device 206 of any preferred construction, but as here shown having a lower roller 207 and an upper roller 208 between which the lifts are passed to receive paste in a well known manner. The lower roller rotates in a paste pot 209 and supplies paste to the upper roller, the paste being maintained in fluid condition by an electric heater (not shown) supplied with current by a conductor 210. The roller 207 is rotated by a belt drive 211 from shaft 5, or in any other desired manner. As each lift is passed between the rollers of the paste applying device to be supplied with paste it is positioned in the heel-former by the operator with its breast against the heel-forming plates 42 and its sides against the respective projections 45, and when the required number of lifts have been superimposed one upon the other to form a heel-blank of the required height, the latter is ready to be moved onto a clamp carrier to be clamped by the plate 90, in the manner previously described. We will now describe the means we employ for securing great accuracy in the conformation, or shape, of the heel-blank while at the same time preventing displacement of the lifts, or of any of them, during the clamping of a heel-blank and its movement for a portion of the distance travelled by the endless carrier.

Referring particularly to Figs. 4 and 14 to 17, a series of heel-engaging back-bars 214 are shown mounted in superimposed relation immediately behind the line followed in their movement by the rear sides of the heel-blanks as they are moved beyond (to the left of) the heel-former 46 by the travelling clamp carriers 41. Each of these back-bars (Fig. 16) consists of a rectangular strip of metal having its heel-engaging edge bevelled, as indicated at 215, and provided on its opposite side at points equidistant from its ends with two arms 216 which are inserted in keepers 217 and secured in position by clamp screws 218. Like the heel-forming plates 42, these back-bars are approximately the thickness of the average lift, and they are positioned in stepped relation, as shown more clearly in Fig. 14, to conform exactly to the incline of the rounded side, or back, of a decked heel-blank. This may be done by backing a heel-blank against the back-bars while they are loose in the keepers, or else positioning a heel-blank, and then pushing the back-bars into engagement with its rear side, after which the clamp screws 218 are turned down to bind the bars in their ad-

justed positions. The back-bars as a whole are adjustable toward and from a positioned heel-blank by the following means (Figs. 14 and 15):

Mounted on the frame member 121 is a bracket 236 on which is secured an upright support 237. Projecting inwardly from opposite ends of this support are two fixed bars 238, and mounted centrally in this support and projecting inward is a screw-threaded rod 239 having secured on its outer end a bevel gear 240. Mounted on the top of support 237, and centrally thereof, is a housing 241 which incloses a rotatable shaft 242 and a bevel gear 243 secured on the lower end of said shaft and in mesh with the bevel gear 240. Secured on the upper end of shaft 242 is a thumb-screw 244. The keepers 217 are secured on the upper side of a base-bar 245 at opposite ends thereof, said base-bar being provided on its under side with apertured lugs 246 which receive and are slidable on the fixed supporting bars 238, and with a central screw-threaded lug 247, in which is engaged the screw-threaded rod 239. It will be readily seen that by turning the thumb-screw 244 in one direction or the other, the base-bar 245 can be adjusted toward or from a positioned heel-blank to insure that the back-bars carried thereby will be properly engaged by the heel-blank when it is moved inward by the heel-former. The bevelled edges 215 enable the back-bars to present an engaging surface conforming to the incline of the heel-blank. When the heel-blank is moved inward by the heel-former to be clamped, the rounded sides of the lifts will engage the stepped back-bars 214 and will be held from displacement when clamped. Moreover, the provision of a fixed engaging surface for the rear side of the heel-blank greatly aids in securing a uniform shape of the heel-blanks, as it forces the breasts of the lifts firmly against the breast portions 42^a of the heel-forming plates, and their sides into engagement with the projections 45 thereof, so that the breast of the heel-blank will present a perfectly flat surface, and the surface of the remainder of the heel-blank will be uniformly inclined. As shown by Fig. 1, one end of the assembled back-bars is directly opposite the heel-former, and the freshly built and clamped heel-blank will slide along the back-bars as its clamp carrier is moved in stages beyond its position opposite the heel-former. As shown, the back-bars are long enough to engage four heel-blanks at one time, so that four separate movements of the endless carrier will occur before a freshly-clamped heel-blank is moved beyond, and out of engagement with, the back-bars. This gives the paste between the lifts time to partially set, so that there is no danger of the lifts becoming displaced under the clamping pressure as the heel-blank is carried around the machine to the discharge point.

For convenience of the operator, we mount above the machine a bin 233 open at its front side and provided with a number of compartments 234 for holding lifts of the various sizes required for building a decked heel. This bin is mounted on columns 235 supported on the frame of the machine.

We wish it to be understood that the invention is not limited to the exact details of construction herein described and illustrated in the drawings, except as may be required by certain of the appended claims, and that various changes may be made in the construction, arrangement and operation of the machine, or its elements, without departing from the spirit of the invention.

We claim:

1. In a heel-building machine, in combination with mechanism for clamping heel-blanks, a base plate on which heel-blanks may be built up, a reciprocable heel-former comprising a fixed wall providing a recess for receiving the lifts and shaping them into the heel-blank at the breast portion thereof as it is being built up, said recess being open at its back to permit free withdrawal of the heel-blanks, said former being movable with a built-up heel-blank over said base plate into co-operative relation with said clamping mechanism, and means controlled by the operator for operating said heel-former to move the heel-blank to a position to be clamped, to operate the clamping mechanism to clamp the heel-blank, and to withdraw the heel-former from the heel-blank and to return it to its original position, in the order named.
2. In a heel-building machine, in combination with mechanism for clamping heel-blanks, fixed heel-engaging means located beyond the same, a reciprocable heel-former engageable with one side of a decked heel, to align the lifts thereof, said heel-former being movable with a built-up heel-blank to maintain the lifts thereof in alignment and to bring the heel-blank under the clamping mechanism and its rear side into contact with said heel-engaging means, and means controlled by the operator for operating said heel-former and clamping mechanism in timed relation to each other, to move the blank against the engaging means and within the clamp, to clamp the same, and to withdraw the heel-former.
3. In a heel-building machine, in combination with mechanism for clamping the heel-blanks, adjustable heel-engaging means located beyond the same, a reciprocable heel-former movable with a built-up heel-blank to bring the latter under the clamping mechanism and its rear side into contact with said heel-engaging means, and means controlled by the operator for operating said heel-former and clamping mechanism in timed relation to each other.
4. In a machine for building decked heel-blanks, in combination with mechanism for clamping the heel-blanks, fixed heel-engaging means located beyond the same comprising a series of back-bars superimposed upon each other in stepped relation to form an inclined engaging surface conforming to the contour and incline of the heel-blank at its rear side, a reciprocable heel-former movable with a built-up heel-blank to bring the latter under the clamping mechanism and its rear side into contact with said heel-engaging means, and means controlled by the operator for operating said heel-former and clamping mechanism in timed relation to each other.
5. In a machine for building decked heel-blanks, a base, in combination with means for clamping the heel-blanks comprising a plurality of travelling carriers movable on the base in stages and each of which has clamping mechanism mounted thereon, fixed heel-engaging means attached to the base, located beyond the line of movement of the clamping mechanisms and having its engaging surface inclined to conform to the incline of the heel at its rear side, a reciprocable heel-former movable with a built-up heel-blank to bring the latter under the clamping mechanism of a carrier at rest and its rear side into contact with said heel-engaging means, and means controlled by the operator

for operating said heel-former and the clamping mechanism of the stationary carrier, and for advancing all of said carriers a single stage, in substantially the order named.

6. In a machine for building decked heel-blanks, in combination with means for clamping the heel-blanks comprising an endless series of travelling carriers movable in stages and each of which carriers has clamping mechanism mounted thereon, fixed heel-engaging means located beyond and parallel to the line of movement of the clamping mechanisms and having its engaging surface inclined to conform to the incline of the heel at its rear side, a reciprocable heel-former movable with a built-up heel-blank to bring the latter under the clamping mechanism of a carrier at rest and its rear side into slidable contact with said heel-engaging means at one end thereof, and means controlled by the operator for operating said heel-former and the clamping mechanism of the stationary carrier, and for advancing all of said carriers a single stage, in substantially the order named, said heel-engaging means being of a length to accommodate a number of heel-blanks at the same time, whereby the first heel-blank moved into engagement with the heel-engaging means will remain in sliding contact therewith until the paste between the lifts has had time to partially set before the heel-blank has been moved beyond said heel-engaging means.

7. In a machine for building decked heel-blanks, in combination with mechanism for clamping the heel-blanks, fixed heel-engaging means located beyond the same and having its engaging surface inclined to conform to the incline of the heel at its rear side, a reciprocable heel-former movable with a built-up heel-blank to bring the latter under the clamping mechanism and its rear side into contact with said heel-engaging means, means controlled by the operator for operating said heel-former and clamping mechanism in timed relation to each other, and means for adjusting the heel-engaging means toward and from the heel-former.

8. In a machine for building decked heel-blanks, in combination with mechanism for clamping the heel-blanks, heel-engaging means located beyond the same comprising a support having a series of back-bars adjustably mounted thereon into fixable positions, a reciprocable heel-former movable with a built-up heel-blank to bring the latter under the clamping mechanism and its rear side into contact with said back-bars, means controlled by the operator for operating said heel-former and clamping mechanism in timed relation to each other, and means for adjusting said support toward and from the heel-former.

9. In a heel-building machine, in combination with a base, mechanism movable on the base for clamping the heel-blanks, heel-engaging means fixed on the base, and located beyond the clamping means, a reciprocable heel-former movable with a built-up heel-blank to bring the latter under the clamping mechanism and its rear side into contact with said heel-engaging means, and means for operating said clamping mechanism to clamp the heel-blank while it is held by the heel-former in contact with said heel-engaging means.

10. In a heel-building machine, in combination with a base, mechanism movable on the base for clamping the heel-blanks, heel-engaging means fixed on the base, located beyond the same and having a straight, extended engaging

surface, a reciprocable heel-former movable with a built-up heel-blank to bring the latter under the clamping mechanism and its rear side into slidable contact with the surface of said heel-engaging means, and means under control of the operator for operating in timed relation said clamping mechanism to clamp the heel-blank while it is held by the heel-former in contact with said heel-engaging means, to return the heel-former to its original position, and to advance the clamped heel-blank a given distance beyond the line of movement of the heel-former with its rear side maintained in sliding contact with the surface of said heel-engaging means.

15. 11. In a machine for building decked heel-blanks, in combination with a base, mechanism movable on the base for clamping the heel-blanks, heel-engaging means fixed on the base, of the height of the heel-blanks, located beyond the clamping mechanism and having a straight, extended engaging surface conforming in its vertical extension with the incline of the heel-blank at its rear side, a reciprocable heel-former movable with a built-up heel-blank to bring the latter under the clamping mechanism and its rear side into slidable contact with said surface of the heel-engaging means, and means under control of the operator for operating in timed relation said clamping mechanism to clamp the heel-blank while it is held by the heel-former in contact with said heel-engaging means, to return the heel-former to its original position, and to advance the clamped heel-blank a given distance beyond the line of movement of the heel-former with its rear side maintained in sliding contact with the surface of the heel-engaging means.

20. 12. In a machine for building decked heel-blanks, in combination with a base, mechanism movably mounted on the base for clamping the heel-blanks, heel-engaging means fixed to the base, of the height of the heel-blanks, located beyond the clamping mechanism and having a straight, extended engaging surface conforming in its vertical extension to the incline of the heel-blank at its rear side, a reciprocable heel-former providing a breast-plate against which the breasts of the lifts are positioned in building the heel-blank, open backwardly from the breasts of the lifts whereby it may be drawn therefrom, and movable with the heel-blank to bring the latter under the clamping mechanism and its rear side into slidable contact with said surface of the heel-engaging means, and means under control of the operator for operating in timed relation said clamping mechanism to clamp the heel-blank while it is held by the heel-former in contact with said heel-engaging means, to withdraw the heel-former to its original position, and to advance the clamped heel-blank a given distance beyond the line of movement of the heel-former with its rear side maintained in sliding contact with said surface of the heel-engaging means.

25. 13. In a machine for building decked heel-blanks, in combination with a base, mechanism movable on the base for clamping the heel-blanks, heel-engaging means fixed on the base, of substantially the height of the heel-blanks, located beyond the clamping mechanism and having a straight, extended engaging surface conforming in its vertical extension to the incline and contour of the heel-blank at its rear side, a reciprocable heel-former having a recess for receiving the breast portion of the lifts as they are superimposed upon each other in building the

heel blank, which recess conforms in incline and contour at its sides to the shape of the heel-blanks at their breast side and provides a breast-plate against which the breasts of the lifts are placed in assembling them into the heel-blank, means for moving said heel-former with a built-up heel-blank to bring the latter under the clamping mechanism and its rear side into contact with said surface of the heel-engaging means to force the lifts into their correct assembled position, and means under control of the operator for operating said clamping mechanism to clamp the heel-blank while it is held by the heel-former in contact with said heel-engaging means.

14. In a machine for building decked heel-blanks, in combination with a base, mechanism movable on the base for clamping the heel-blanks, heel-engaging means fixed on the base, of substantially the height of the heel-blanks, located beyond the clamping mechanism and having a straight, extended engaging surface conforming in its vertical extension to the incline and contour of the heel-blank at its rear side, a reciprocable heel-former having a recess for receiving the breast portion of the lifts as they are superimposed upon each other in building the heel-blank, which recess conforms in incline and contour at its sides to the shape of the heel-blanks at their breast side and provides a breast plate against which the breasts of the lifts are placed in assembling them into the heel-blank, means for moving said heel-former with a built-up heel blank to bring the latter under the clamping mechanism and its rear side into contact with said surface of the heel-engaging means to force the lifts into their correct assembled position, and means under control of the operator for operating said clamping mechanism in timed relation to clamp the heel-blank while it is held by the heel-former in contact with said heel-engaging means, to return the heel-former to its original position, and to advance the clamped heel-blank a given distance beyond the line of movement of the heel-former with its rear side maintained in contact with said surface of the heel-engaging means.

15. In a heel-building machine, a heel-former comprising two series of heel-forming plates each series being adapted to be clamped in superimposed relation in line with each other, and the two series being adapted to form a breast plate, each of which plates is provided with a breast portion and a projection extending beyond its breast portion, and the two series of superimposed series of projections forming with the breast portions an adjustably sized recess the sides of which are adapted to engage the sides of a heel lift as it is placed in position with its breast against said breast portions.

16. In a heel-building machine, a heel-former comprising two series of heel-forming plates each series being adapted to be adjustably clamped in superimposed relation in line with each other, and the two series being adapted to form a breast-plate, each of which plates is provided with a breast portion and a projection extending from its breast portion, and the two series of superimposed series of projections forming with the breast portion a recess the sides of which are adapted to engage the sides of a heel lift as it is placed in position with its breast against said breast portion.

17. In a heel-building machine, a heel-former comprising two series of heel-forming plates, of substantially the thickness of the lifts used in

building the heels, adapted to be adjustably clamped with the plates in superimposed relation in line with each other, each of which plates is provided with a breast portion and a projection extending from its breast portion, and the superimposed series of projections being arranged in stepped relation, whereby the two series are adapted to provide a recess for receiving the forward portion of the heel lifts as their breasts are positioned against said breast portions, the sides of which recess conform in incline and contour to the shape of the heel-blank being built.

18. In a heel-building machine, a heel-former comprising two series of heel-forming plates, of substantially the thickness of the lifts used in building the heels, the two series being laterally adjustable and the plates of each series being mounted in superimposed relation in line with each other whereby the two series may provide a breast-plate, each of which plates is provided with a projection extending from its breast side, and the superimposed series of projections being adjustable by their plates to provide a recess having walls diverging upwardly in stepped formation whereby to conform in incline and contour to the shape of a heel-blank built by inserting heel lifts of successively increasing size in said recess with their breasts positioned against said breast-plate.

19. In a heel forming machine, a base, a clamping means adapted to receive a decked heel formed of lifts with cement between them and to compress together the lifts thereof, said clamping means being adapted to apply force to the heel tending to extrude the same from the clamp, said clamping means being movable on the base, heel-engaging means disposed adjacent the clamp to oppose said extrusion, said last means being rigid to hold the lifts on the clamps against yielding to said extrusion force.

20. In a heel forming machine, a base, a clamping means adapted to receive a decked heel formed of lifts with cement between them and to compress together the lifts thereof, said clamping means being adapted to apply force to the heel tending to extrude the same from the clamp, said clamping means being movable on the base, and heel-engaging means disposed adjacent the clamp to oppose said extrusion, said heel-engaging means being shaped to engage the decked heel at a plurality of vertically disposed points, and being rigid to hold the lifts in the clamp against yielding to said extrusion force.

21. In a heel forming machine, a base, a clamping means adapted to receive a decked heel formed of lifts with cement between them and to compress together the lifts thereof, said clamping means being adapted to apply force to the heel tending to extrude the same from the clamp, said clamping means being movable on the base, and heel-engaging means disposed adjacent the clamp to oppose said extrusion, said heel-engaging means being on the base, and means to displace the clamping means along the base, the engaging means being elongated in the direction of said displacement to remain in contact with the heel for a substantial period until the cement between the lifts has set to resist said extrusion.

22. In a heel forming machine, a base, a clamping means adapted to receive a decked heel formed of lifts with cement between them and to compress together the lifts thereof, said clamping means being adapted to apply force to the heel tending to extrude the same from the clamp, said clamping means being movable on the base,

and heel-engaging means disposed adjacent the clamp to oppose said extrusion, said heel-engaging means comprising a series of superposed members clamped to the base to project at variable distances toward the heel, whereby to engage a plurality of lifts of said decked heel, and said heel engaging means being of rigidity, to hold the lifts in the clamp against said extruding force.

23. In a heel forming machine, a base, a heel former having a shape to receive and position heel lifts to form one side of a decked heel, said heel former being fixed in said shape, means to

reciprocate the heel former on the base from a heel building position to a heel clamping position, heel-engaging means on the base adjacent the heel clamping position of the heel former, said heel-engaging means being shaped to receive and engage the decked heel at points opposite the side engaged by the heel former, and to hold the lifts in set position, and clamping means engageable with the decked heel while the same is against the heel-engaging means.
